DESIGN FOR A PACKAGE DISPLAY STAND

Louis N. Levinsohn, New York, N. Y.

Application May 17, 1933. Serial No. 48,136

Term of patent 7 years

To all whom it may concern:

Be it known that I, LOUIS N. LEVINSOHN, a citizen of the United States, and a resident of the city of New York, (borough of Manhattan), in the county of New York and State of New York, have invented the new, original, and ornamental Design for a Package Display Stand, of which the following is a specification.

Reference is had to the accompanying drawing, in which—

The figure is a perspective view of a package display stand showing my new design.

I claim:

The ornamental design for a package display stand substantially as shown.

LOUIS N. LEVINSOHN.
